[57] CLAIM

The ornamental design for a hair setting apparatus, substantially as shown and described.

DESCRIPTION

FIG. 1 is a front elevational view of the body of a hair setting apparatus showing my new design;
 FIG. 2 is a right side elevational view thereof;
 FIG. 3 is a left side elevational view thereof;
 FIG. 4 is a top plan view thereof; and
 FIG. 5 is a bottom plan view thereof;
 FIG. 6 is a front elevational view of the apparatus with the brushing attachment mounted;
 FIG. 7 is a left side elevational view thereof;
 FIG. 8 is a right side elevational view thereof;
 FIG. 9 is a bottom plan view thereof; and
 FIG. 10 is a top plan view thereof;
 FIG. 11 is a front elevational view of the apparatus with the iron attachment mounted;
 FIG. 12 is a left side elevational view thereof;
 FIG. 13 is a right side elevational view thereof;
 FIG. 14 is a bottom plan view thereof; and
 FIG. 15 is a top plan view thereof.
